CLAIM

The ornamental design for a rug pad, as shown and described.

DESCRIPTION

FIG. 1 shows a top and side perspective view of a rug pad showing my new design.

FIG. 2 shows a bottom and side perspective view thereof.

FIG. 3 shows a top plan view thereof.

FIG. 4 shows a bottom plan view thereof.

FIG. 5 shows a left side view thereof.

FIG. 6 shows a right side view thereof.

FIG. 7 shows a front side view thereof; and,

FIG. 8 shows a rear side view thereof.

The broken line is for the purpose of illustrating portions of the article and form no part of the claimed design.

1 Claim, 4 Drawing Sheets(56)
